Marvin O. Bink

Attorney

UNITED STATES PATENT OFFICE.

ALEXANDER G. JANUS, OF MORGANTOWN, WEST VIRGINIA.

TOOTHBRUSH.

Application filed February 26, 1925. Serial No. 11,832.

This invention relates to a novel article of manufacture in the form of a tooth brush.

What I purpose to do is to provide a simple and inexpensive tooth brush which is adapted to form a part of what is to be known as a dental kit, the kit containing the brush being in the form of a small packet which may be and preferably is dispensed from a conventional form of vending machine to be supplied on travelers' conveyances, such as railway trains, steamboats, and the like, whereby to afford a temporary tooth brush and other articles for emergency use.

Other features of advantage of the invention will become apparent from the following description and drawings:

In the claims:

Figure 1 is a perspective view of a tooth brush constructed in accordance with the present invention,

Figure 2 is a sectional view taken approximately upon the plan of the line 2—2 of Figure 1.

Referring to the drawings, it will be seen that the improved brush comprises a handle 1 and a head 2, together with the customary bristles 3. The handle and head are formed from a single piece of material. The material employed is compressed paper and this is rendered moisture and weather-proof in any suitable manner. The material preferably employed is similar to that used in the construction of sanitary paper spoons frequently seen, there being enough "body" to the material to render it sufficiently rigid to withstand the comparatively rough usage to which it is put.

In forming the improved brush, the material is pressed to provide a channel-shaped handle, and elongated cup-like head. In manufacturing the brush, the cup serves to receive a quantity of water-proof glue or other adhesive, for securely fastening the bunches of bristles to the head. The surrounding marginal flange serves to prevent displacement of the bristles and constitute the novel retainer for the glue. In practice, the depth of the cup varies according to the length of the bristles so that a desired amount of cement or its equivalent can be used for assuring proper anchorage of the bristles in place. The gist of the idea is in supplying a device capable of temporary use at the lowest cost possible, so that when a traveller inadvertently forgets to take his dental kit with him, he can obtain one from a dispensing machine on the train, the kit including the novel brush herein described and shown.

Having thus described my invention, what I claim as new is:

A tooth brush adapted for temporary use by travelers and the like, said brush comprising a single piece of water proofed paper of a consistency capable of rendering it comparatively rigid, said paper being formulated into a channel shaped handle and an elongated cup-like head, a plurality of bunches of bristles fitted into said head, and a water proof adhesive in said head and securing said bristles in place.

In testimony whereof I affix my signature.

ALEXANDER G. JANUS.
